UNITED STATES PATENT OFFICE.

PETER R. GONSKY, OF CHICAGO, ILLINOIS.

COMBINATION PHONOGRAPH AND LAMP.

1,353,469.

Specification of Letters Patent. Patented Sept. 21, 1920.

Application filed June 17, 1919. Serial No. 304,927.

To all whom it may concern:

Be it known that I, PETER R. GONSKY, a subject of the King of England, residing at Chicago, in the county of Cook and State of Illinois, have invented certain new and useful Improvements in Combination Phonographs and Lamps, of which the following is a specification.

The invention has for an object to give a construction by which a sound arm is provided that is also usable to form one side of an ornamental lamp support, concealing its nature as a sound arm when so used. It is an important aim also to give an improved sound modulating means especially applicable to a phonograph of this character.

Additional objects, advantages, and features of invention will appear from the construction, arrangement and coördination of parts as represented in one embodiment of the invention, hereinafter described and shown in the drawings, wherein,

Figure 1 is an elevational view of the invention in use for reproducing a record,

Fig. 2 is a similar view showing the device solely as a lamp,

Fig. 3 is a view similar to Fig. 1, with the shade portion removed,

Fig. 4 is a view similar to Fig. 2 with the shade removed.

Fig. 5 is a detail section showing the sound modulating valve,

Fig. 6 is a top view of a central fragment of the shade frame.

Fig. 7 is a top view of the tubular post 14 and parts mounted thereon positioned for utilization of the sound arm and transcribing devices, as in Fig. 3.

Fig. 8 is a fragmentary vertical sectional view of the upper part of the post and the elbow mounting thereon including the member 25,

Fig. 9 is a sectional view of the elbow 26 and the mounting of the sound arm therein.

There is illustrated a lamp providing an ornamental base 10 in which any suitable mechanism may be concealed for rotating and supporting a sound record 11 and which may be provided with an ornamental cover 12 by which the record 11 may be covered and concealed when not being reproduced.

The casing 10 is in the form of an urn, having arms 12' extended from opposite sides thereof in a form suggestive of handles, while upstanding tubular posts 13 and 14 re-

spectively are supported upon these arms. Through the post 13 and its respective arm 12, electric wires may be extended for energizing electric light bulbs of suitable character provided in the upper part of the apparatus, as will be described. Upon the post 13 there is mounted an ornamental bracket arm 15, supporting lights 16 and having a suitable fastening 17 thereon above the lights by which a shade 18 (as shown in Figs. 1 and 2) may be secured in place. The bracket arm 15 terminates in a vertical end portion 19 upon which the lamp and bracket device 17 are mounted, the member 17 forming a terminal element on the part 19. In the lower part of the post 14 there is mounted on a transverse axis a small butterfly valve 20, the post comprising in the main a cylindrical tube upon the lower part of which there is revolute a collar 21. The valve 20 is formed with a longitudinally slotted arm 22 at one side close to its pivot, this arm receiving therethrough a pin projected through a suitable slot in the tubular post and being mounted upon the inner surface of the sleeve 21 which is revolute upon the post and suitably knurled upon the outside for manipulation whereby its rotation will oscillate the valve 20 to open or close it. It should be noted that the arm 22 and its slot extend obliquely with respect to the plane of the valve 20 and the slot through which the arm 22 projects, this permitting the valve to be moved into full open position, in a plane coincident with the axis of the tube 14. Upon the upper end of the post 14 there is mounted for rotation on a vertical axis a hollow ball-shaped element 25 corresponding to a similar thick element 25' upon the opposite post, the ball 25 having a hollow sleeve 25^a projected loosely into the post 14. At one side an elbow 26 is mounted upon the ball 25, revolute upon a horizontal axis with respect to the ball, its outer arm having rotatably mounted therein the base of a sound arm 27 identical in form with the bracket arm 15 before mentioned, the bracket arm 15 being rigidly connected with the ball member 25 by means of an elbow connection 26.

The arm 27 it will be seen is in the shape of an ogee curve, and has upon its swinging end the usual sound box and other reproducing mechanism for coördination with the record 11, as at 28. The arm 27 is of such length that when the ball member 25 is

turned with the elbow 26 extending off therefrom at one side of the plane in which the posts 13 and 14 are disposed, and the arm 27 rotated so that when the connected part 5 of the elbow 26 is horizontal, or nearly so, a needle mounted in the sound reproducer will engage the record, and the needle will extend in a direction nearly or quite coinciding with the direction of the sound record grooves. It should be further noted that the length of the bracket arm 15 is such that when the ball 25 is rotated on a vertical axis to bring the elbow 26 to the inner side of the post 14, and the arm 27 rotated in the 10 elbow to bring its inner end into close proximity with the part 19 of the bracket arm 15, the sound arm and supporting post will have the same symmetrical relation to the vertical axis of the complete device as the parts 13, 15, and 25'. Upon the upper end of the 20 bracket arm 15 there is provided an engaging device 30 constructed to engage with a part of the sound or reproducing device 28 to hold it in raised position when engaged therewith. In the present instance, the device 30 consists of a headed pin under which a part of the sound box may be sprung, this pin being engaged in a casting or other suitably milled fitting 31 including the upper 25 part of the bracket arm 15, the lights 16 being mounted upon short lengths of tubing screwed into the fitting 31, the fastening 17 comprising a screw threaded into the upper part of the fitting 31.

30 The shade 18 includes a spider frame 32 at its upper part having a central plate 34 apertured to receive the screw 17 down-

35

wardly therethrough, by which means the shade is secured against casual detachment and supported properly in position. 40

What is claimed:

1. In a machine and lamp of the character described, a base, a bracket arm mounted thereon and extending upwardly into a central position over the base, lamp appliances 45 carried thereby, a sound arm having a form similar to that of the bracket arm, said sound arm movable at times into an opposing position corresponding symmetrically with that of said bracket arm, and means to releasably hold the sound arm in the last named position. 50

2. In a sound reproducing machine and lamp, an urn containing a mechanism and a platen rotatable in a horizontal plane, hollow handle arms on the urn, extensions upon one arm to support lamp devices centrally over the urn, lamp devices on the extensions and wires extended to said devices, extensions of like form upon the other arm 55 which are tubular and jointed and a terminal reproducer device thereon, whereby the reproducer may be moved into engagement with a record upon said platen and oscillated thereon, at times, and to be at other times 60 in symmetrical opposition to the first named extension. 65

In testimony whereof I have affixed my signature in presence of two witnesses.

PETER R. GONSKY.

Witnesses:

W. HERCAL,
J. Jwaskevicz.
